UNITED STATES PATENT OFFICE

157,545

HOLDER FOR VACUUM COFFEE MAKERS

Jack G. Temmer, Appleton, Wis.

Application August 11, 1948, Serial No. 148,049

Term of patent 3½ years

(Cl. D44—26)

To all whom it may concern:

Be it known, that I, Jack G. Temmer, a citizen of the United States, residing at 1324 West Franklin Street, Appleton, in the county of Outagamie and State of Wisconsin, have invented a new, original, and ornamental Design for a Holder for Vacuum Coffee Makers, of which the following is a specification, reference being had to the accompanying drawing, forming part thereof.

In the drawing:

Fig. 1 is a perspective view of the holder for vacuum coffee makers, showing my new design;

Fig. 2 is a top view thereof; and

Fig. 3 is a side elevational view thereof.

I claim:

The ornamental design for a holder for vacuum coffee makers, substantially as shown.

JACK G. TEMMER.
